UNITED STATES PATENT OFFICE

2,435,518

TOBACCO CURING FURNACE

John D. Simpson and Charles M. Ball,
Mount Airy, N. C.

Application September 26, 1944, Serial No. 555,845

2 Claims. (Cl. 237—53)

1

This invention relates to new and useful improvements in the art of tobacco curing and more particularly to a specially constructed furnace for producing heat in the process of curing tobacco.

The principal object of the present invention is to provide a simple yet thoroughly efficient furnace for installation in tobacco barns, said furnace being constructed in such a manner as to be more durable and furnish a more even distribution of heat than is now possible through the use of present-day tobacco curing furnaces.

The present invention contemplates a furnace provided with an arrangement of flues carrying smoke from the furnace and in this manner distributing heat uniformly and also allowing for a direct passage of dry heat from the furnace proper for the purpose of preventing any sweating and splotching of the tobacco being cured.

Other important objects and advantages of the invention will become apparent to the reader of the following description.

In the drawings—

Figure 1 represents a top plan view of the flue pipe arrangement.

Figure 2 is a fragmentary vertical sectional view through the structure shown in Figure 1.

Figure 3 is a fragmentary end elevational view of the barn shown in section in Figure 2, but having a portion broken away to disclose the furnace and flues.

Figure 4 is a longitudinal vertical sectional view through the furnace.

Figure 5 is a transverse vertical sectional view taken substantially on the line 5—5 of Figure 4.

Figure 6 is a transverse sectional view taken substantially on the line 6—6 of Figure 4.

Referring to the drawings wherein like numerals designate like parts, it can be seen that the present invention embodies two main factors, namely, a flue arrangement generally referred to by numeral 5 and a special furnace construction generally referred to by numeral 6.

The furnace embodies a base structure consisting of side walls 1, 1, a front wall 8 and an ash door 9 in said wall 8, the wall 8 representing the lower portion of a main front wall 10.

Longitudinally extending angle members 11, 11 are riveted or bolted as at 12 to the upper edge portions of the side walls 1, 1 and the horizontal portions of these angle bars 11 serve to support an elongated grate 13, this grate being removably disposed on the bars 11 as suggested in Figure 6.

The furnace has an outer shell 14 which embodies side walls, a, a and a curved top b. The shell 14 is secured by bolts or rivets 15 to the

flanged portions 16 of the front wall 10 and a rear wall 17, the rear wall 17 at its lower portion having a flue attachable neck 18.

Numeral 19 generally refers to an inner shell which is divided transversely and longitudinally into a plurality of sections. The upper edges of the sections are grooved as at 20 and these grooved portions are disposed against an elongated tie rod 21. The grooved portions of the sections of the inner shell 19 have ears 20a which are bolted together as at 22, thus clamping the grooved portions of the sections against the tie rod 21.

The side portions of the sections of the inner shell 19 are preferably formed with inwardly pressed portions 23 to permit expansion and contraction of this shell structure.

At the rear end of the interior of the furnace is a short floor structure 24 which has a downwardly and arcuate shaped intermediate offset 25 so that smoke from the furnace can pass downwardly and out through the neck 18 to the flue pipe 35. The offset portion 25 of the bottom 24 has a slotted lug 26 through which a bolt or the like 27 can be disposed through the rear wall 17, for holding this short bottom structure in definite position.

An upstanding deflector plate 28 is provided at the forward end of the offset bottom 24, and a baffle plate 29 is suitably secured in spaced relation to the back wall 17 so that the heat of the furnace fire carried by the outblowing smoke and products of combustion will not unduly heat the rear wall.

It can now be seen that the front wall 10 in addition to having the ash door 9, has a door 30 through which coal can be shoveled on to the grate or on to the fire bed.

Further, that portion of the front wall 10 between the inner shell 19 and the outer shell 14 has openings 31 therein to allow air to pass into the chamber 32 between said shells.

The rear wall 17 is likewise formed with openings 33, it being preferable that the openings 33 be somewhat higher than the openings 31 in the wall 10. It can now be seen, that air can enter the furnace through the wall 10 by way of the openings 31, from the outside of the barn A and pass along the chamber 32 where it is heated to a dry state and this dry heat can pass through the openings 33 in the rear wall 17 and directly pass into the barn, this dry heat serving principally to prevent any squirting or splotching of the tobacco being cured.

The flue arrangement 5 consists of a pipe 35

extending from the flue collar 18 and this has a pair of branch pipes 36, 36 extending laterally therefrom to join with parallel pipes 37, 37 which extend backwardly toward the furnace and have inwardly disposed pipe extensions 38, 38 meeting a common conduit 39 just over the furnace 6 which extend to a vertical flue or chimney 40, at the outside of the barn A. This arrangement of the flue pipes offers an uniform application of heat to the contents of the barn.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A furnace for tobacco curing comprising an outer shell, a spaced inner shell, end walls, said shells being spaced from each other, openings in the end walls to permit ingress and egress of air, a grate in the inner shell, a downwardly offset bottom at one end of the grate and a flue attaching structure at the offset bottom, said inner shell comprising lateral sections, joined at their top along a vertical, longitudinal plane, a longitudinally extending, tubular recess formed in the adjacent surfaces of said lateral sections, said lateral sections constituting a plurality of longitudinal aligned portions, telescoping joint means between said portions, and tension means disposed in said tubular recess for aligning and securing in compression said portions, and clamping means for securing said lateral sections upon said tension means.

2. Apparatus for applying heat for tobacco curing by both radiation and convection, comprising, a furnace having a rear wall, a combustion chamber, an outlet for combustion products at the rear of said combustion chamber, a detach-

able, downwardly offset bottom between said combustion chamber and said outlet, means comprising a conduit system connected to said outlet for disseminating heat from said furnace by radiation, and means for disseminating heat from said furnace by convection and including an air jacket surrounding said combustion chamber, means for causing a flow of air through said air jacket, to establish convection currents of heated air, and a baffle means removably carried by said detachable bottom and disposed between said combustion chamber and said outlet for determining the relative proportion of the heat disseminated by radiation through said conduit system and by convection through said air jacket, said aligned transverse sections being divided and mechanically secured together along a longitudinal vertical plane, and a longitudinally extending tie rod, disposed in the said longitudinal vertical plane for securing the sections in longitudinal, axial alignment, said air jackets comprising a plurality of abutting, transverse sections, aligned axially of said furnace, the abutting ends of said sections constituting telescopic joints.

JOHN D. SIMPSON.
CHARLES M. BALL.
